DEVICE FOR THREADING THE POINTS OF SCREW BLANKS

Filed Jan. 14, 1927

DAVID LEONARD SWENDSÉN
INVENTOR:

By *Ott H. Munk*
his Attorney.

UNITED STATES PATENT OFFICE.

DAVID LEONARD SWENDSEN, OF NORRKOPING, SWEDEN.

DEVICE FOR THREADING THE POINTS OF SCREW BLANKS.

Application filed January 14, 1927, Serial No. 161,071, and in Sweden October 2, 1926.

The present invention relates to means for threading the points of blanks for carpenters' screws, in which the cutting tool is moved first parallel to the axis of rotation 5 of the screw blank and then while threading moved at an angle to the same, and in which after the completion of the threading operation the tool is locked at its point of travel most remote from the center of the blank, 10 whereby it can be returned to initial working position without damaging the threaded point of the blank.

The object of the present invention is to provide an improved arrangement of this 15 kind. This is achieved by mounting the tool or tools on inclined slides carried by a slide rest which is movable in a direction parallel to the axis of rotation of the screw blank, the arrangement being such that the 20 said slide rest partakes in the initial cutting movement and then abuts against a stop whereby during the continuation of the movement the inclined slides are caused by suitable connection to move relatively to the 25 slide rest and thus to move the tool or tools in a direction at an angle to the axis of rotation of the blank, and that the movement of the tool or tools with respect to the slides rest after the completion of the threading is 30 stopped and the tool locked in that position so that the return to initial position is effected without harming the cut threads.

The tool is locked in the above described 35 position by means of a spring pawl which when the threading of the point is completed engages a stop on the rear of the slide so that the tool is held in the same position on the slide that it holds at the completion of the threading during the 40 return movement to initial working position. When the slide rest reaches its initial position, the inclined slide with tool or tools is moved in to working position by mechanism hereinafter more fully described.

The invention is shown in the accompanying drawing, which illustrates an embodiment thereof, partly in side view and partly in section.

The rod 1 is carried forward by a cam or 50 the like and brings with itself in its movement through the spring 2 the slide rest 3 which is fixed to a sleeve loosely mounted on said rod, until the flange 4 at the other end of said sleeve is stopped against the 55 fixed bearing 5, whereafter the movement of the rod is transferred through the link 6 to

the inclined slide 7, which is movable in the slide rest 3. Hereby the rotating blank, 7' is threaded by the tool 7" at the desired angle with respect to the centre line or axis 60 of the blank. When the tool has passed the blank, the stop lever or pawl 8 is spring pulled inwardly behind the stop 9 on the slide 7. The parts retain this relation during the return motion of rod 1, until the pawl 8 through contact with the angled surface 10 of the bearing 5 is disengaged from the stop 9 and slide rest 3 is stopped by abutment of a flange on the inner end of the aforesaid sleeve with bearing 5, where- 70 after the inclined slide 7 during the return motion is brought back to its initial working position. The purpose of this arrangement is to move the tool on its return move- 75 ment parallel to the rod or the centre line of the blank.

The mechanism described is mounted in the machine or lathe in any suitable manner. This can be readily accomplished by any one skilled in the art, it being merely 80 necessary to provide means, preferably driven from the main drive of the machine, for reciprocating the shaft 1, such as a cam. The bearing 5 can be anchored or fixed in any convenient manner to the bed 85 plate or other suitable part of the lathe or machine, whilst the slide rest 3 may be adapt- ed to slide along the bed plate.

Having now particularly described and ascertained the nature of my said invention 90 and in what manner the same is to be performed, what I claim is:—

1. In a device for threading the points of screw blanks in combination, cutter carrying means, movable parallel to the axis of the 95 blank to be threaded, a cutter movably mounted on said carrying means, means for moving said cutter carrying means and said cutter, as a unit, parallel to the axis of said blank prior to the start of the cutting operation, means for stopping said cutter carrying means, means for moving said cutter at an angle outwardly from the axis of said blank during the threading operation, means for locking said cutter in a position most 100 remote from the axis of said blank, means for returning said cutter in locked position to the beginning of its stroke and means for releasing said cutter locking means at the end of the return movement whereby said 105 cutter is replaced in its starting position.

2. In a device for threading the points of

screw blanks, in combination, a slide rest movable parallel to the axis of the blank to be threaded, an inclined slide mounted on said slide rest, a cutter mounted on the outer 5 end of said slide, means for moving said slide rest and said cutter, as a unit, parallel to the axis of said blank prior to the start of the cutting operation, means for stopping the slide rest, means for moving said cutter 10 through said slide during the cutting operation, whereby it follows an outwardly inclined path, a lug mounted on the inner end of said slide, a spring pressed pawl mounted on said slide rest and coacting with said lug 15 to lock said cutter in its outermost position, means for returning the cutter to the beginning of its stroke in locked position, and means for releasing said pawl at the end of the return stroke.

20 3. In a device for threading the points of screw blanks, in combination, a reciprocating cutter actuating rod movable parallel

to the axis of the blank to be threaded, a flanged sleeve loosely mounted on said rod and journaled in a bearing which coacts 25 with the flanges of the said sleeve to limit its motion, a flange on the inner end of said rod, a coiled spring between said sleeve and said flange, a slide rest carried by the outer end of said sleeve, an inclined slide mounted 30 on said slide rest, a link connecting said slide to the outer end of said rod, a cutter fixed to the outer end of said slide, a lug on the inner end of said slide, a spring actuated pawl mounted on said slide rest and coacting 35 with said lug to lock said cutter in its outermost position at the end of the forward stroke of said rod, and an inclined shoulder on said sleeve bearing coacting with said pawl to release said cutter at the 40 end of the return stroke of said rod.

In testimony whereof I have affixed my signature.

DAVID LEONARD SWENDSÉN.
